UNITED STATES PATENT OFFICE.

REGINALD ARTHUR HOLLINGWORTH, OF BEESTON, ENGLAND, ASSIGNOR TO AMERICAN TEXTILE COMPANY, INC., OF PAWTUCKET, RHODE ISLAND, A CORPORATION OF RHODE ISLAND.

DESIGN FOR LACE.

Application filed August 24, 1928 Serial No. 27,957. Term of patent 7 years.

To all whom it may concern:

Be it known that I, REGINALD ARTHUR HOLLINGWORTH, a citizen of Great Britain, and a resident of Beeston, Nottingham, England, have invented the new, original and ornamental Design for Lace, of which the following is a specification.

Reference is had to the accompanying drawing, forming part thereof.

The figure is an elevation of lace, showing my new design.

I claim:

The ornamental design for lace, substantially as shown.

Signed at the city of Nottingham, in the county of the same city, England, this 21st day of July, A. D. 1928.

REGINALD ARTHUR HOLLINGWORTH.
